UNITED STATES PATENT OFFICE.

JAMES MOORE K. LETSON AND FRANK WATTS BURPEE, OF VANCOUVER,
CANADA.

CAN-CAPPING MACHINE.

SPECIFICATION forming part of Letters Patent No. 629,574, dated July 25, 1899.

Application filed June 30, 1898. Serial No. 884,866. (No model.)

To all whom it may concern:

Be it known that we, JAMES MOORE K. LETSON and FRANK WATTS BURPEE, citizens of the Dominion of Canada, residing in the city of Vancouver, in the Province of British Columbia, Canada, have invented certain new and useful Improvements in Can-Capping Machines, of which the following is a specification.

10 This invention relates to improvements in machines for applying the caps or covers to cans; and among other objects it has for its purpose to provide a machine of this character which will apply the caps to a vast number of cans in a short space of time, and by slight adjustment to some of the parts of such machine cans of various dimensions may be capped.

The invention consists in certain combinations and details of construction and arrangement of parts, such as will be hereinafter first described in detail and then be specifically pointed out in the appended claims, reference being had to the accompanying drawings, in

25 which—
Figure 1 is a vertical section of our improved machine, parts being in elevation, the view being taken practically on the line 2 2 on Fig. 2. Fig. 2 is a plan view of the machine. Fig. 3 is a side elevation of the machine, viewed in the direction of the arrow on Fig. 4. Fig. 4 is a horizontal section on the line 3 3 of Fig. 1. Fig. 5 is an enlarged detail plan view of the feed mechanism for the cans and for the caps. Fig. 6 is an enlarged detail view of the means for applying the cap to the can. Fig. 6^a is a detail side view, parts being sectioned practically on the line a a of Fig. 6. Fig. 7 is a detail view of the table

40 carrying the mechanism for connecting the cap and the can from above and below, respectively. Fig. 8 is a vertical section of the parts shown in Fig. 7, taken on the line 4 4 of such figure. Fig. 9 is an enlarged detail plan view illustrating the mechanism forming the opening through which the caps are introduced to the can. Fig. 10 is a detail section taken on the line 5 5 of Fig. 9. Fig. 11 is a detail end elevation of a portion of the 45 cam-spacing mechanism. Fig. 12 is a detail

plan view of the same, and Fig. 13 is a detail edge view of a portion thereof.

Referring now to the accompanying drawings, in which like numerals and letters indicate like parts in all the figures, 10 indicates 55 a horizontal frame or bed supported on legs 11. Suitably arranged integrally with the frame 10 is an upwardly-extending pillow 12, and continuing for a suitable distance upward is a spindle 13.

14 indicates a rotatable carrier mounted on the spindle 13 and resting on the pillow 12, and such carrier has its under beveled periphery provided with teeth which mesh with the beveled gear 15 on the horizontally-disposed shaft 16, suitably journaled under pillow-blocks 17, fixedly held on the frame 10. The carrier 14 has radial arms 14^a, the projecting ends of which have apertures, in which seat spindles 18, having can-supporting disks 70 19, the purpose of which will hereinafter appear. Resting upon and securely fixed to the carrier 14 is a table 20, having openings 21 in vertical alinement with the can-supports 19. (See Fig. 1.)

24 indicates a carrier secured upon the table 20, provided with radial arms 24^a, in which are held spindles 25, having pendent disks 26, adapted to press downward upon the can-caps, as will hereinafter be more fully described. 80

Rigidly secured to the top of the spindle 13 is a frame 27, having a radial cam-rim 28.

29 indicates collars adjustably secured to the top of the spindle 25, said collars having spindles projecting inwardly, upon which are 85 mounted antifriction-rollers 30, adapted to engage the cam 28, whereby the spindle 25 will be raised and lowered, for a purpose hereinafter explained.

Secured on the under sides of the radial 90 arms of the carrier 24, with its outer periphery extended toward the centers of the spindles 25, is a ring 31, having a toothed peripheral edge and recesses at the point of contact with the spindle 25 to form seats therefor, the 95 object of which will be seen later.

Suitably secured above the frame 10 by supporting-brackets 32 is a stationary table 33, having an upwardly-projecting lug 33^a, to which is secured a bracket 34, through the 100

- extended end of which passes a shaft 35, the axis of which is placed at the same distance from the circle described by the spindles 25 as the semidiameter of such circle.
- 5 Securely fixed to the depending end of the shaft 35 is a wheel 36, having on its outer sides can-recesses 36^a, which, as will be clearly understood from Figs. 1 and 4, are directly in line with the periphery of the can-supports 19.
- 10 On the upper end of the shaft 35 and resting on the upper side of the bracket 34 is secured a wheel 37, the plane of its lower side being arranged a slight distance above the upper plane of the table 20. The purpose of the wheel 37 is to feed the caps to the cans, and the openings or seats for the same are placed directly above the seats for the cans in the wheel 36; but, as clearly shown in Fig. 1, the seats for such caps do not extend to the 15 upper surface of the wheel, the object of this being to prevent the caps from rising up or being jarred from their proper position while being conveyed to the openings 21 in the table 20.
- 15 25 indicates a bracket or table secured to the top of the table 33, said table 38 having a cap-chute 38^a, which is placed on an even plane with the top of the table 20, and the cap-recesses 37^b in the wheel 37 are arranged 20 to engage and slide the said caps to the openings 21.
- 20 Secured on upwardly-projecting lugs 37^a on the can-feed wheel 37 and on a plane level with and made to engage a toothed ring 31. 25 is a like toothed ring 39, which receives movement from the ring 31, which is secured within and made to turn with the table 20, and as the rings 39 31 are of the same diameter the can and cap feeding wheels 36 37 will travel 30 at the same speed as the said table 20, and the recesses in such wheels contact in vertical alinement with the cap-openings 21 and the supports 19, it being thus seen that by this arrangement of parts when the machine 35 is in operation cans and caps will be fed to the supports 19 and to the openings 21 simultaneously.
- 35 To enable the peripheral edge of the ring to receive half of the diameter of the spindles 50 85, recesses 39^a are provided therein, and by means of like recesses in the ring 31 the said spindles will be allowed to rise and fall between the contacting edges of the rings 39 31 without undue friction.
- 40 55 In operation to prevent the cans as they are transferred from the recesses 36^a in the wheel 36 to the support 19 being pushed beyond alinement with the openings 21 we provide guides 40 in the nature of radial arms 60 secured to the support or stem 20^a of the table 20 and having can-holding recesses therein. To prevent in like manner the caps being pushed beyond or from alinement with the openings 21, brackets 41 are secured to 65 the table at the rear or inner sides of such openings. By this arrangement it will be noticed that a can is placed beneath each open-
- ing of the table and a cap is placed over such opening as the respective recesses in the wheels 36 37 meet their respective recesses of the guards 40 and brackets 41 beneath and above the table 20.
- As shown in Figs. 5 and 6, when a cap is introduced to its position over the opening 21 in the table the spindle carrying the disk 26 will be elevated, as shown by dotted lines, thus allowing the cap A to be pushed beneath the disk. To conveniently hold the said cap and prevent vibration at this point of the operation, the said disk 26 is fixed to 80 a slideable stem 42, which is arranged within the spindle 25, said stem 42 being controlled in a sufficient vertical movement by a screw 43, passing through a slot 25^a in the spindle. A spiral spring 44 in the opening pressing 85 downwardly upon the stem will normally keep it down; but when the cap A is inserted the disk 26, together with the spindle 25, is elevated (see dotted lines) just above the plane of such cap, and, as shown in Fig. 5, the spindle 25, carrying the disk 26, at this point will immediately begin to descend by reason of the antifriction-rollers 30, laterally projecting from the collars 29, passing downward through the opening 28^a in the cam 28 to the under 90 side thereof, when the disk 26 will assume the position shown in Fig. 6, engaging the cap A, and while the said spindle 25 is descending the disk 26 will be upon the top of the cap and bearing down in proportion to the tension of the spring 44 until the said spring is driven back, when a rigid force will be exerted by the lower end of the spindle 25 contacting with the disk 26. The stem 42 and the spring 44 act as a holder for the cap and prevent it from being displaced before the positive downward force is exercised by the spindle 25 and the said cap is in a proper position to receive can B, which is being simultaneously pushed upward by the support 19, actuated by the spindle 18, being pushed upward through the carrier 14 by the cam or chase 46 on the member 47. The member 47 is of an arc form and is provided at the ends with cam or sloping portions 46, and at the center it has a level plane, and as such member 46 47 is arranged in the track of the spindles 18 such spindles are pushed upward and lowered at proper intervals. It will be noticed that at the point where the spindles 18 are pushed up the spindles 25 will be depressed by reason of the cam 28, as before mentioned, so that a can and a cap are simultaneously driven together, and such contact will take place within the opening 21 in 110 the table 20.
- 115 To prevent the caps from dropping down through the opening 21 before such opening is properly contracted to seat the cap, as will be understood presently, we provide slideable plates 48. (Best shown in Figs. 6 and 9.) These plates 48 are arranged to work in recesses 22 in the table 20, and the forward sides of such plates have a dovetailed form,

the opposite sides of such plates having projections 48^a, whose extreme rearward portions lie and are allowed to slide beneath the brackets 41, such arrangement preventing the 5 plates 48 from rising upward or allowing them to have a reciprocating action to and from each other.

Pivottally connected to upwardly-extending ears 41^a of the opposite ends of the bracket 10 41 are triggers 49, the depending ends of which have rounded portions 49^a, which lie in recesses in the rearwardly-projecting portions 48^a of the plates 48, and by reason of the rearwardly-disposed arms 49^b being engaged 15 between the fixedly-disposed forks of the projection 25^b on the inner side of the spindle 25 when such spindle 25 is raised and depressed the plates 48 will be reciprocated over the opposite edges of the cap-opening 21.

20 It is obvious that when the plates 48 cover the opening 21 the disk 26 is elevated and the can-support 19 in a position to receive a can B, and at the same time a cap A will be disposed upon the plates 48, and as such plates 25 are withdrawn, owing to the bevel-chase 48^b on the inner ends thereof, the cap will be gradually lowered while the can is being raised to meet it.

To prevent the spindles 25, carrying the 30 disks 26, from turning, pins 50, vertically secured to the radial arms of the carrier 24, are provided, which pins loosely pass through the shanks of the collars 29. To permit a free vertical movement of the spindles 25 and keep 35 the rollers 30, as also the projections 25^b, in a proper operative position or alinement, the said rollers 30 are made to engage the track-cam 28, while the projections 25^b engage the inner ends of the arms 49^b of the bell-crank 40 levers 49, as best shown in Fig. 6.

As better shown in Figs. 6, 9, and 10, recesses are arranged in circular form around the openings 21 in the table 20, and having an even axis to the axis of such openings are 45 removable members or jaws 51. These jaws are disposed at an angle to each other and have their edges, which form the inner sides of the openings 21, made beveled or bell-mouthed from above and below, the upper sides forming upwardly-projecting rims or lips 51^a, and at a suitable distance below the upper plane of the lips 51^a, within the contracted annular opening, is a ledge or rim 51^b, designed to receive the edges of the cap A, such ledge being of sufficient depth to allow the upwardly-forced can B to enter the cap A without the possibility of the edges of the cap and can engaging edge on, and thus make flawed work.

It is evident that in order to properly receive the cans and caps between the jaws such jaws must expand and contract the opening 21. This is done by a movement of the jaws directly at right angles with the axis of said opening, which movement is controlled 60 by rigidly-fixed pins 20^b in the table 20 extending into slots 51^c, arranged at right angles to the axis of the opening 21 and on the

upper sides of jaws 51. To cause the jaws 51 to advance and recede to and from the axis of the openings 21 is arranged a ring 52 beneath the jaws, and this is supported and allowed to turn upon supports 53, secured to the under side of the table intermediately between the openings 21 and having their sides projecting beneath and supporting the rings 75 70 52, as clearly shown in Figs. 6, 8, and 10.

At proper intervals on the upper side of each ring 52 are curved grooves 52^a, which receive depending tongues 51^d, said tongues and grooves having their axes differentially 80 placed to the axis of each opening 21, so that when the ring 52 is revolved slightly, as will be shown presently, the jaws 51 will advance and recede, and thus contract and expand each opening 21.

Connected to a rigidly-fixed pin 52^b on the under side of the ring 52 is an arm 54. (See dotted lines, Figs. 4 and 7.) This arm 54 is slidably arranged in a slot on the upper side of each supporting-plate 53 and arranged radially from the axis of the table 20, with its upper plane even with the lower plane of the rings 52 to allow for the sweep of the arc of the circle described by the pin 52^b. As the arm is pushed in and out a slot in the deflected part of the arm is provided, so that the ring may roll back and forth without causing undue resistance. On the extreme end of the arm is arranged a small antifriction-roller 55. In practice a number of these 95 arms 54 are provided, as shown, and as the table 20 is revolved the rollers 55 are brought in contact with the cam 56, rigidly held on supporting-stems 57, which will push the arms back at the point 56^a (see Fig. 4) and will 100 draw them forward at the point 56^b by reason of such cam passing over to the inner side of the rollers, as at 56^c. It will be observed that when the point 56^a of the cam is reached by the roller 55 on the arm 54 the opening 105 controlled by such arm will be over the member 47, and the spindle 18, carrying the can-support 19, will at this point descend, and the pushing in of the jaw 54 opens the jaws 51 and allows the can, which has received its 110 cap, to descend to the normal plane, when the can will be received between the forks of the delivery-bracket 58, which will be explained more fully hereinafter.

As before mentioned, at the part of the cam 115 56^a the arm is pushed inwardly. This is caused by the cam-track being on a tangent to the table 20 and 56^a being the closest point to such table; but as the roller 55 travels forward it is engaged on the opposite side by the 120 wedge 56^b, which draws the arm outward, and thus closes the jaws ready to receive the next cap and guide the can into the same. When the can and the cap take their respective places on the support 19 and over the opening 125 21, said support 19 will be at its normal or lowest plane (see Fig. 1) and the spindles 25 will be elevated and allow the cap to take its place, and consequently the said cap will lie 130

- upon the slidable plate 48; but as the table, with the carriers, passes around the rollers 30 will engage the lower side of the cam 28 by passing through the opening 28^a. This will 5 throw the arms of the triggers 49 downward and withdraw the plates 28, and the cap A will then drop to its position on the annular rim 51^b, the disk 26 holding the lid secure. At this time the can-support 19 will drive the can 10 into the cap, as shown in Fig. 6, and as the can is carried around the cam 56 will engage the arm 54 and open the jaws 51, thus releasing the can, and simultaneously the spindles 18 will pass down the chase 46 to the member 15 47, thereby delivering the can back to its normal plane with a cap applied thereto, this operation being repeated by the mechanism connected with each opening for each revolution of the table 20.
- 20 Arranged to pass over and lie in a recess in the table 33 is a can-feed belt 59, passing around a pulley 60 on the shaft 61, having journals 62. In practice the cans are conveyed to the machine on this belt in the direction 25 indicated by the arrow, and one can is received into each of the recesses 36^a in the wheel 36, and as such wheel revolves said can is conveyed around to where one of the can-supports 19 on the carrier 14 is engaged, when 30 said support will receive and convey the can away.
- 35 To control the can in its proper track as it is being pushed around, an arc-shaped guide 63 is adjustably fixed at the proper distance from the wheel 36 by brackets 64 and 65, which pass through slots 33^b and 33^c in the table 33.
- 40 The can, in traveling around within the guide 63, will pass over the belt 59, and to provide that it should not again contact with the belt the track or guideway is gradually raised and the belt is covered by a thin plate 66, which is inserted flush with the plane of such slideway, so the can will pass smoothly there- 45 over.
- 45 The caps A are conveyed to the opposite side of the machine on a plane with the top of the table 20 by a belt 69, (see arrow, Fig. 5,) which belt passes over a pulley 70, secured 50 on the shaft 71, journaled in a hanger 72, integral with the table 33.
- 55 As the recesses 37^b in the wheel 37 receive a cap such cap will be conveyed to one of the openings 21 in the table 20 and a can 55 will have taken its place beneath, when the operation of applying the cap will be performed and the can will be delivered through the track 58 onto the belt 73, which passes over a pulley 74, fixedly held on the shaft 61.
- 60 The delivery-track 58 consists of a pillow-58^a, which supports and secures the track on the plane with the can-supports 19, it also having extending arms projecting inwardly, so that the advancing can will be received there- 65 tween, the arm 58^b being adjustably secured to the other member by bolts passing through slotted lugs 58^c and into the horizontal part

of the other portion. This adjustment is for the purpose of receiving cans of various dimensions.

To prevent more than one can at a time from crowding against the feed-wheel 36, (see Fig. 5,) a spacing device is adjustably arranged on one side of the feed-belt 59. This consists of an L-shaped bracket 75, secured by a set-screw 76 passing through a slot 77 in a projecting lug 33^c of the table 33, and pivotally fixed to the under side of the L-shaped brackets 75 are members 78, connected together by pins working in slots in the loose end thereof, so that when one member is moved motion will be imparted to the others.

Pivoted on seats surrounding the axis of the toggle members 78 are fingers 79, the extremities of which are normally pressed forward by the springs 80. The object in thus holding the fingers 79 by spring-pressure is to prevent the said fingers 79 from damaging a can when oscillated should the can lie directly in the path of one of them, which damage would occur were the said fingers rigidly held on the body members 78. An oscillating movement is imparted to the spacing mechanism by means of a member 82, pivoted on the pin 83, said lever having rollers 84, which are held to alternately engage with the cam-wheel 85, which causes the parts 78 to turn back and forth, and as the fingers 79 are pivotally connected to the members 78 and normally pressed forward by springs 80 they will be drawn forward alternately, the center one being projected, while the end ones are withdrawn, and vice versa. One of the members 78 connects with the upper end of the lever 81 by the member 82.

It will be observed that there are four cams on the wheel 85, the same as the number of recesses for the feed-wheel 36 and openings 21 in the table 20, and therefore for each revolution of the cam-wheel 85 four cans will be fed to the machine; and now comes one of the most important features of our machine.

As a can is pushed around within the arc 63 it will contact with the fixedly-disposed arms of the bracket 86, pivoted on a stem 87^a, (see Fig. 5,) and by reason of such arms projecting in the path of the cans each can that passes will cause a rigidly-fixed arm 88 on the top of the said bracket to rock forward and back. A coupling connection 89 causes movement to be imparted to the spacing mechanism 90, which is adjustably fixed to the projecting lug 91 on the cap-table 38. It will thus be seen that each can releases its own cap—as, for instance, when a can B engages the bracket 86 a cap A will be released and as the next recess in the wheel 36 contains said can the released cap will take the seat in the cap-feed wheel 37 directly over such can, and consequently the can and cap 130 will be transferred to their respective positions beneath and on the table 20.

The spacing mechanism 90 is a duplicate of the device 75, which reverses to engage

the caps coming the opposite way. (See arrow.)

The coupling or connecting device 89 has longitudinal adjustment which is effected by the section 89, having a threaded shank taking into the section 89^a, and the jam-nut 89^b secures the section at the length desired.

It is observed that by changing the parts which actively engage the cans and caps and substituting parts of a suitable size to engage the cans to be capped or topped our machine may be adjusted to operate on cans of various dimensions, it also being evident that our machine may be employed to advantage in can-making for applying the bottoms thereto.

In the operation of our machine motive power is applied to the loose pulley 92, which has a fixed clutch-coupling 93, and its counterpart 94 is arranged to slide on a feather on the shaft 16 by means of a lever 96, pivotally connected with the fixed bracket 97. When the coupling is drawn together, movement is imparted to the vertical revoluble sections by the bevel-gears 14 and 15, and movement is transferred to the shaft 35 through the toothed wheels 31 and 39.

A chain belt 98 connects a rigidly-fixed sprocket 99 on the shaft 16 with a sprocket 100, rigidly connected with the belt-wheel 70, which carries the belt 69 and feeds the caps to the machine.

Motive power is imparted to the belt-wheel 101 in the direction of the arrow. This communicates movement to the can-feed belt 59 and to the delivery-belt 73. The cans are placed upon the belt 59 and the caps on the belt 69, and as the machine operates the cans are first fed to the machine and then the caps, each can releasing one cap, the can and cap being brought together and discharging upon the belt 73, which conveys it away.

We have in most respects specifically described the construction and relative arrangement of the several parts of our improved machine; but we do not desire to be understood to confine ourselves to such specific construction and arrangement, as such changes or modifications may be made in practice as fairly fall within the scope of our invention.

Having thus described our invention, what we claim, and desire to secure by Letters Patent, is—

1. A can-capping machine, comprising a rotating frame having reciprocally-movable can-seats; a rotatable table having openings for the cans; means for feeding the caps in position; vertically-reciprocal cap-pressers, and means for simultaneously elevating the can-seats and depressing the cap-pressers as specified.

2. A can-capping machine, comprising a rotating frame having can-seats; a rotatable table having openings for the cans; means for keeping the cap in position, and vertically-reciprocal cap-pressers mounted on the frame, rotatable with the can-carrying frame,

and means for reciprocally moving the cap-pressers in engagement with the caps and holding them during the operation of delivering the same to a take-off belt, substantially as described.

3. In combination with a machine for applying the caps to cans, a rotatable table having openings for the cans and means for applying caps thereto; of a frame 24, having radial arms with spindles arranged therein, depending disks on the ends of such spindles; a rigidly-fixed frame 27, secured to the top of the spindle 13, on which the table and the frames 14 and 24 rotate, said frame having a track 28, for rollers, around the upper and lower sides of its rim, rollers 30, arranged to turn on the shanks of collars which are secured to the top of the spindles 25, and such rollers to take around the track 28, such track taking on the under side of the rim of the frame 27, for a distance vertically above the fixed cam 46, on the bed, whereby the disks will be depressed and the can-supports will be elevated simultaneously, as set forth.

4. A rotatable table, having openings therein, in combination with reciprocating disks above and below such openings; of jaws forming the annular rims of the said openings, a ring supporting said jaws, having grooves in the upper side thereof, beneath each respective jaw member, tongues depending from the under sides of said jaws and engaging in the grooves, said grooves and tongues being placed at differential axis to the openings, for the purposes set forth.

5. In combination with a rotatable table, having openings therein, with reciprocating disks vertically above and below such openings, of jaw members around said openings, rings connected with tongue-and-grooved mechanism with such jaws, said tongues and grooves arranged on arcs with a differential axis to the openings; of support members 53, secured beneath the table and supporting the said rings, arms 54, passing through slots in the upper sides of the members 53, and engaging fixed pins 52^b, depending from the said rings, antifriction devices on the projecting ends of said arms, and a cam 56 arranged on one side of the table, which will engage and push the said arms inward and draw them forward whereby the rings 52 will be turned for a distance back and forth, and thereby the openings will be expanded and contracted, as set forth.

6. In combination with a rotatable table, having openings therein, with reciprocating can and cap disks beneath and above such openings; of jaw members arranged at an angle around the said openings; said jaws being bell-mouthed from below, and slightly flared from above, the contracted annular center having rims for the seats of the can-caps, and upwardly-projecting lips around such seats; of rigidly-fixed pins depending from the table 20, to within slots 51^c, in said jaw members, said slots being arranged at an angle to each

other, and with their slideways at right angles to the axis of the openings in the table, as specified.

7. In combination with a rotatable table 5 having openings therein, with reciprocating can and cap disks, below and above such openings; of members for contracting and expanding the openings as specified; brackets 41, secured to the table at the rear sides of the 10 openings, plates 48, arranged to reciprocate in slots on opposite sides of the openings, triggers 49, pivotally secured to oppositely-fixed ears on the brackets 41, and the horizontally-disposed arms of the triggers engaging with 15 projections on the spindles which support the disks above the openings, as set forth.

8. In a machine of the class described having a rotatable table with openings therein for the contact of cans and caps; the combination of spindles having disks 26 arranged above such openings; and means for raising and depressing the same; oppositely-disposed projections secured on the rear sides of the said spindles 25, brackets 41 secured to the 20 rear sides of the said openings, the inner sides of these brackets being of arc form on the same contour to the openings; slidable plates 48 arranged on opposite sides of the said openings, triggers 49, pivotally connected to 25 upwardly and oppositely disposed ears on the brackets 41, and connecting with the projections on the spindles 25 and the slidable plates 48, whereby, when the spindles rise and fall the said plates will be reciprocated 30 over the opposite sides of the openings.

9. In a machine of the class described, having a rotatable table with openings therein, spindles arranged in a carrier 24 secured to said table, said spindles having disks on their 40 depending ends; collars 29 rigidly fixed to the upper ends of the said spindles, shanks on said collars which project inwardly, rollers on the ends of the shanks engaging with a track on the fixed frame 27, vertical apertures 45 through the said shanks of the collars and guides 50, rigidly fixed in the arms of the frame 24, and passing upwardly through the apertures in said shanks, of the collars, whereby the spindles 25, will be prevented from 50 turning, as set forth.

10. In combination with a rotatable table having openings therein, with reciprocating can and cap disks below and above such openings, slidable stems 42 arranged within the 55 spindles 25 above the table, cap-holding disks 26 on the depending ends of the stems 42, coil-springs 44, for normally pressing these holders downward; slots 25^a, in the sides of the spindles, and screws 43 inserted through 60 such slots and secured in the spindles 42, whereby their movement will be controlled.

11. In combination with a rotatable table having openings for cans, can-supporting disks arranged beneath in a frame integral 65 with the table, a fixed table or can-guideway 33, supported and secured by brackets 32, on a level plane with the can-supports below the

table; of an inwardly-projecting horizontally-disposed bracket 34, secured to one end of said table, a shaft 35 vertically journaled in such bracket, a wheel 36 having can-recesses 36^a, therein, said recesses being placed in alinement with the openings in the table; of a cap-feeding wheel 37, secured on the upper end of the shaft 35, and having recesses there-in directly above the recesses in the wheel 36, and a toothed wheel 39, secured to upwardly-projecting brackets on the cap-feeding wheel, which toothed wheel meshes with a like wheel 31, secured to the frame 24, above the rotatable table, as set forth.

12. In combination with a rotatable table having openings therein, can-supporting disks below such openings, cap-engaging disks above such openings; of a can-feeding wheel having 85 its recesses engage in alinement below the recesses or openings in the table, can-guards 40, arranged to prevent the cans from being pushed beyond such alinement; a table or bracket 38, secured upon the table 33, having 90 a slideway for caps, a cap-feeding wheel 37, having recesses vertically arranged above the recesses or seats in the wheel 36, and means for communicating movements to these wheels simultaneously with the movement of 95 the table 20, whereby a can will be placed on the support below the opening therein, and a cap will be placed over such opening, as set forth.

13. In combination with a rotatable table 100 having openings therein, and can-supports below such openings, on a plane with a fixed table 33, a groove in such table for the passage of a belt 59, and an arc-guide 63, fixed at even radii with the diameter of a can-feeding wheel 36, and means for changing the radius of such guide, as set forth.

14. In a machine of the class described, in combination with a rotatable table having openings for the contact of cans with their caps, a groove for the passage of a belt 59, arranged to pass over a fixed table, an adjustable bracket 75 having reciprocating fingers 79, arranged in mechanism therein, such mechanism connecting with a cam-wheel, by 115 an oscillatory lever, whereby the fingers will be thrust back and forth over the said belt 59, as and for the purposes set forth.

15. A fixed table 33 having a belt passing over a groove or recess in the same, means 120 for imparting movement to such belt, a can-spacing mechanism on one side thereof and means for pushing cans, at intervals around a common center from the belt on one side to pass over to the other side without contacting 125 with such belt, by a plate intervening.

16. In a device for feeding caps to cans, in a machine as described, the combination of a table 33, and a recess therein for a belt traveling thereover, a can-feeding wheel having 130 seats for cans which push the cans forward over the table, a guide 63, arranged to control the cans, a bracket 86, pivotally fixed without the track of the cans, oppositely-disposed

arms on said bracket projecting into the path of the cans; of a cap-feeding belt 69, arranged over a bracket or slideway 38, an adjustable bracket 91, secured to a lug on such bracket 38, and a finger-cap-releasing mechanism arranged on the bracket 91, the same being connected to the arm 88, as shown and described, whereby each can engaging the arms of the bracket 86, will release its own cap.

17. In combination with a rotatable table, having openings therein for the passage of caps, can-supports arranged below said openings, and seats for the caps in such openings, a fixed table 33 and means for passing cans thereover on a plane with the can-supports beneath the rotatable table, a bracket 38 arranged above the table 33, a groove for a cap-feed belt 69, which takes thereover and around a pulley 70 on a shaft 71, and means for imparting movement to such pulley by a sprocket-belt 98, taking over a wheel 99, secured on the shaft 16, said belt 69 arranged on a plane with the table 20, and means for simultaneously depositing a can and a cap respectively below 25 and above one of the said openings, as set forth.

18. In a can-capping machine, the combination of a rotating frame having reciprocally-movable can-seats, a rotatable table 30 having contractible openings for the cans and provided with cap-seats, means for simultaneously feeding a can to one of the seats and a cap to its seat, vertically-reciprocal cap-pressers, and means for simultaneously elevating the can-seats and for depressing the cap-pressers, and for releasing and delivering the same to a belt, substantially as described.

19. In combination with a rotatable table

having openings therein, each opening being formed by members arranged at an angle to each other and having tongues on the under sides resting in grooves in a movable ring, which are placed at a differential axis to the opening, and the whole being supported by brackets or plates 53; an arm passing through such plate diametrically in line with the table, a rigid pin secured to said ring and engaging in a slot in the deflected end of such arm and means for forcing the arm in and out, whereby the jaw member will contract and expand 50 the opening as set forth.

20. In a can-capping machine, the combination of a rotary table having openings, reciprocating disks above the openings, reciprocating plates at opposite sides of the openings for supporting the caps, and connections between the disks and the plates, whereby the plates will be withdrawn when the disks are moved downward, substantially as described.

21. In a can-capping machine, the combination of a rotary table, having openings, vertically-reciprocating disks located above the openings and adapted to engage the caps, reciprocating plates located at opposite sides 65 of the openings for supporting the caps, and levers connecting the disks and the plates, whereby the latter will be withdrawn when the former move downward, substantially as described.
